UNITED STATES PATENT OFFICE

FRANK G. BROTH, OF KOHLER, WISCONSIN, ASSIGNOR TO KOHLER COMPANY, OF KOHLER, WISCONSIN, A CORPORATION OF WISCONSIN

BATHTUB DRAIN

Application filed June 19, 1931. Serial No. 545,441.

The invention relates to bathtubs and to drains therefor, and has for an object the provision of a bathtub of simple construction having but few parts and fittings, and so arranged as to facilitate the mounting and cleaning of the trap and the installation of the waste valve and its operating means.

Another object of the invention is to provide a bathtub having waste valve operating means including a rod insertable through the overflow opening and passage to its operating position and having a lower end portion which is detachably secured to a valve upwardly removable from the drain opening.

A further object of the invention is to provide a bathtub including an integrally formed overflow passage having a plurality of selectively usable outlets facing in different directions to facilitate connection to a drain conduit.

A further object is to provide a bathtub having a drain opening which is controlled by a mechanically operated valve including a resilient rubber valve element adapted to seat directly on the vitreous surface of the tub, thus avoiding the necessity for mounting a metal valve seat member in the tub.

The invention further consists in the several features hereinafter set forth and more particularly defined by the annexed claims.

In the accompanying drawings,

Fig. 1 is a vertical sectional view of an end portion of a bathtub constructed in accordance with the invention;

Fig. 2 is a vertical sectional view of the upper end portion of the bathtub showing a removable connecting member for the waste valve in an intermediate passing position;

Fig. 3 is a detail view of the waste valve connecting member;

Fig. 4 is a detail bottom view of the tub, parts being broken away and parts being shown in section;

Fig. 5 is a detail sectional view taken along the line 5—5 of Fig. 1 showing a typical cross-section of the overflow passage;

Fig. 6 is a fragmentary sectional elevation of a modified form of waste valve;

Fig. 7 is a sectional view thereof taken along the line 7—7 of Fig. 6, and

Fig. 8 is a transverse sectional elevation of another modified form of waste valve.

In these drawings, the numeral 10 designates a cast iron bathtub of the built-in type having a vitreous enameled surface and having formed integral therewith in the same casting the walls of an overflow passage 11, which at its upper end communicates with the interior of the tub through an overflow opening 12. The lower walls of the overflow passage extend below the bottom of the bathtub and are there provided with an internally threaded annular outlet 13, which is axially aligned with a large drain opening 14 formed in the bottom wall of the tub.

A short exteriorly threaded nipple 15 of large diameter extends through the drain opening 15 and at its upper end is provided with a tapered peripheral flange 16 disposed in sealing engagement with the upper surface of the bottom wall of the tub. A nut 17 is threaded onto the nipple from below to clamp the nipple in position. The nut 17 may be introduced through the overflow opening 12 and downwardly through the overflow passage 11.

An inverted cup-shaped pop-up valve 18 slidably fits in the nipple 15 and is provided with a peripheral flange 19 at its upper edge, which has a releasable sealing engagement with a seat formed at the upper face of the nipple. A series of drain openings 20 are formed in the cylindrical side walls of the valve.

The lower end of the valve has a detachable threaded connection with a ring 21, which is formed integrally with a bent rod 22 extending upwardly within the overflow passage 11. To facilitate the attachment and detachment of the valve with respect to the ring 21, the valve is provided with a tool-receiving slot 23 in its upper face. The rod 22 has a hook-shaped upper end 24, which is pivotally secured to a crank pin 25 carried on a rock shaft 26. The rock shaft 26 is journalled in a downwardly opening hood 27, which conceals the overflow opening 12 and is attached to the wall of the tub in any suitable manner. An operating handle 28 is secured to the outer end of the rock shaft 26. The valve-

operating rod 22 is introduced into place by being passed through the overflow opening 12 and downwardly within the overflow passage 11, as seen in Fig. 2.

- 8 When access is desired to interior passages and parts therein for purposes of inspection or cleaning, it is only necessary to unscrew the pop-up valve member 18 from the ring 21 and to lift the valve member out of the nipple 15, thus permitting easy access to the passages through the comparatively large drain opening in the bottom wall of the tub.

10 In addition to the downwardly opening outlet 13, the integrally formed overflow passage is also provided with a rearwardly opening interiorly threaded outlet 29 and a forwardly opening interiorly threaded outlet 30, the latter being offset laterally from the outlet 13 and having a slight downward pitch, so 20 that a pipe with an elbow attached can be turned without interfering with the tub. The axes of the outlets 13 and 29 are arranged at right angles to each other, and the outlet 29 is so located that a pipe connected thereto will pass over the upper edge of an adjacent floor beam. One of the three outlets is selected for connection with the drain piping, the other two being closed by pipe plugs of conventional type.

30 If a trap is desired, it can be attached to the downwardly opening outlet 13. In this position, the trap can be swung about the vertical axis of the outlet to any angle in order to facilitate connection with the drain pipe and to clear adjacent floor beams. The connection to the sewer can be made from any angle which is not possible with a drain of the usual type, in which connection is made into one side of a T communicating 40 with the drain outlet and the overflow. The trap may be readily cleaned from the inside of the tub through the large aligned drain openings after removing the valve 18.

45 In the modified form of valve shown in Figs. 6 and 7, the enameled surface of the downwardly converging drain opening 14' forms a valve seat engageable by the tapered side walls of an inverted cup-shaped valve 31 of rubber or other suitable resilient material, thus obviating the necessity for fitting a metal valve seat member to the tub. The valve 31 is clamped between metal washers 32 and is secured by a screw 33 to the upper end of a valve stem 34, the lower end of which has a reduced threaded extension 35 detachably threaded into the lower end of an opening rod 22' somewhat similar to the rod 22 in Fig. 1. The valve stem 34 is provided with radially extending vertical wings 36 which center the valve stem in the drain opening 14'.

50 The modified form of valve shown in Fig. 8 is similar to that of Fig. 6 except that the valve element consists of a resilient rubber disk 31' which is adapted to seat on the enameled bottom surface of the tub about the drain opening 14'.

55 The overflow, being cast integral with the tub, eliminates the use of all separate overflow pipes. This results in a saving of expensive brass parts, considerably reduces the time necessary for installation by reason of the lesser number of joints and fittings which must be made, and also as there are less joints the tendency to leak is minimized. The 70 construction is such as to eliminate the use of rubber sealed joints, which become leaky when the rubber deteriorates.

75 Since all working parts are accessible and removable from the inside of the tub, repairs can be made in the bathroom itself and it is unnecessary to disturb two rooms for this purpose, which is an important feature especially in hotels and apartment buildings. Furthermore, it renders unnecessary the usual 80 practice of providing a removable panel in the wall of an adjoining room for access to the overflow and drain piping when repairs or adjustments are to be made.

85 The drain passages may be easily cleaned through the large drain openings after removing the valve. Because of the small amount of brass required, the outlet passages of the tub can be made considerably larger than is now possible without material additional 90 cost. This results in larger flow passages and quick draining of the bathtub, which assists in carrying away all of the floatage before it can adhere to the sides of the tub. As 95 seen in Fig. 5, the overflow passage is formed by converging walls presenting a generally triangular cross-section, thus reducing the area of the inner surface of the passage, while still permitting easy insertion of the valve-operating rod. The surface of the passage liable to fouling is thereby considerably 100 reduced.

105 The few parts used are of relatively simple character and the cost of manufacturing the tub is substantially reduced, not only by requiring less expensive brass, but also by the elimination of much machining, tapping, fitting of parts, and inspection and packing operations at the factory. The valve seat 110 nipple 15 is mounted in place at the factory, where it can readily be reamed or otherwise surfaced after installation to properly fit the valve, thus insuring a much better fit than if the seat is surfaced before the nipple is applied to the tub, since there is always some distortion of the seat by drawing the nipple down onto the somewhat irregular enameled 115 surface of the tub. The entire assembly can be packed in one package for shipping, which minimizes loss and damage and assures that the fittings arrive at the job the same time as the tub. This obviates the usual practice 120 of shipping the brass fittings for the tub in a separate package.

What I claim as new and desire to secure by Letters Patent is:

1. A bathtub having a drain opening and an overflow opening and having an integral passageway connecting said openings, a valve-operating means including a rod bent to be capable of entering through the overflow opening and passing through the passageway to a position beneath the drain opening, and a valve fitting on the drain opening and passing therethrough and screw threaded onto said rod, whereby the valve and rod may be assembled from above by entering them through the respective openings to their engaging relation.
2. A bathtub having a drain opening and an overflow opening and having an integral passageway connecting said openings, a valve-operating means including a rod bent to be capable of entering through the overflow opening and passing through the passageway to a position beneath the drain opening, said rod having a threaded ring beneath said drain opening, and a valve fitting on the drain opening and passing therethrough and threaded onto said ring, whereby the valve and rod may be assembled from above by entering them through the respective openings to their engaging relation.
3. A bathtub having a drain opening and a communicating overflow passage, valve operating means including an actuating member in said passage having a laterally extending part below said drain opening, and a valve member in said drain opening screw threaded onto the laterally extending part of said actuating member.
4. A bathtub having a drain opening and a communicating overflow passage, valve operating means including an actuating member in said passage having a laterally extending annular portion below said drain opening, and a valve member in said drain opening having a tubular portion substantially concentric with said annular portion and detachably secured thereto.
5. A bathtub having a drain opening and a communicating overflow passage, valve operating means including an actuating member in said passage having a laterally extending annular portion below said drain opening, and a valve member in said drain opening having a tubular portion screw threaded onto said annular portion.

In testimony whereof, I affix my signature.

FRANK G. BROTHZ.
